UNITED STATES PATENT OFFICE.

WILLIAM H. CLEMES, OF CLEVELAND, OHIO, ASSIGNOR TO THE TAYLOR & BOGGIS FOUNDRY COMPANY, OF SAME PLACE.

COMBINED WICK-TUBE AND BURNER-PLATE FOR OIL-STOVES.

SPECIFICATION forming part of Letters Patent No. 495,022, dated April 11, 1893.

Application filed March 24, 1891. Serial No. 386,246. (No model.)

To all whom it may concern:

Be it known that I, WILLIAM H. CLEMES, a citizen of the United States, and a resident of Cleveland, county of Cuyahoga, and State of Ohio, have invented certain new and useful Improvements in a Combined Wick-Tube and Burner-Plate for Oil-Stoves, of which the following is a specification, the principle of the invention being herein explained and the best mode in which I have contemplated applying that principle, so as to distinguish it from other inventions.

In the annexed drawings:—Figure I represents a perspective view of my improved wick-tube and burner-plate; Fig. II, a horizontal section on the line II—II in Fig. III; Fig. III, a longitudinal section on the line III—III in Fig. II, showing a portion of the reservoir-top in section; Fig. IV, a transverse section on the line IV—IV in Fig. II; Fig. V, a transverse section of another form of wick-tube and burner-plate embodying the same invention.

In the drawings the letter A indicates the wick-tube and B the burner-plate. Both of said parts are made in one piece and stamped or struck up from one piece of sheet-metal, preferably and usually sheet-brass, in the usual, well known manner or in any suitable manner. The wick-tube is contracted toward its upper, open end to form a long, narrow slot through which the wick may pass, and the sides of the tube gradually flare or expand toward its lower end to form a housing for the wick-raiser C which is journaled therein. The burner-plate B, which is integral with the wick-tube, is formed into a shoulder b at the lower end of the wick-tube and into a downwardly-bent flange b', said shoulder and flange forming a cap which may fit upon a neck, d, upon the top D of the oil reservoir of the stove, surrounding the slot d' through which the wick depends into the reservoir.

There will be no leakage of oil or gas between the wick-tube and burner-plate, and subsequent annoyance and danger, as are liable to be where the wick-tube and burner-

plate are secured together by solder or other means; and this point is a great advantage in my wick-tube and burner-plate, as the joints in the usual forms of oil-stoves, between the wick-tube and the burner-plate, are very liable to open and leak on account of the severe heat to which they are exposed.

There will be no danger in my improved wick-tube and burner-plate of seams opening at the ends or middle of the tube and plate, as the entire structure is seamless and cannot, consequently, open without being cut or broken.

This combined wick-tube and burner-plate is very simple to construct and will, consequently, be capable of manufacture at a comparatively low price, being simply stamped out of a piece of sheet-metal and requiring no jointing, seaming or soldering.

My improved article thus has the advantage of simplicity, and consequent cheapness of manufacture; and of simplicity of construction, and consequent strength, durability and perfection in its operation.

Instead of forming the burner-plate into the cap illustrated in Figs. I to IV, inclusive, the burner-plate may be flat, as illustrated in Fig. V and may be secured in a recess, d², 75 surrounding the slot d' in the reservoir-top. The advantages of this tube and burner-plate are the same as of the one described above, the difference of construction being simply for the purpose of adapting it to a different 80 form of reservoir-top.

I claim as my invention—

A seamless wick-tube and seamless burner-plate formed integral with each other and of one piece of stamped sheet-metal, substantially as set forth.

In testimony that I claim the foregoing to be my invention I have hereunto set my hand this 20th day of March, A. D. 1891.

W. H. CLEMES.
